Attorney

UNITED STATES PATENT OFFICE

FRIEDRICK GRAFFENBERGER, OF MILWAUKEE, WISCONSIN

BLADE EDGER

Application filed September 11, 1929. Serial No. 391,857.

This invention relates to blade edgers.

One object of the present invention is the provision of an effective edger for blades of razors, knives and other keen edged instruments, which is of simple design and construction so as to permit its manufacture at an extremely low cost.

Another object is the provision of an edger which will renew the cutting edge of an instrument by realigning the several fibres contained therein to thereby remove the irregular saw-toothed edge, that is characteristic of a dull blade, without removing any of the metal by abrasion. By the use 15 of an edger constructed in accordance with the teachings of the present invention, I have found that a blade may be re-edged many times and still maintain its original keenness.

20 A further object is to provide an edger which will be self-cleaning during the edging operation to preclude the collection of dirt or foreign matter that would otherwise impair the utility of the device.

25 Other objects and advantages will appear from the following description of an illustrative embodiment of the present invention.

In the drawings:—

30 Figure 1 is a side elevational view of an edger (drawn on a magnified scale) constructed in accordance with the teachings of the present invention.

Fig. 2 is a top plan view of the edger.

35 Fig. 3 is a vertical sectional view taken on the line 3—3 of Fig. 1.

The edger shown in the accompanying drawings comprises a pair of rotatable coaxial disks 10 fixedly mounted in facial contact on a hub 11. The disks 10 coact to form the edging means for the blade and function in a manner to be hereinafter more specifically described. A bushing 12 which is slightly longer than the hub 11 is inserted 40 through a centrally disposed longitudinal aperture 14 in the hub 11 to form a bearing upon which the hub 11 and disks 10 may rotate freely as a unit. The bushing 12 is permanently secured between the extremities 45 of a bifurcated handle 15 by means of a

bolt 16 which passes freely through an aperture 17 in one arm of the handle and an axial bore 18 in the bushing 12. The bolt 16 is then directed through a threaded aperture 19 in the other arm of the handle 15. The head of the bolt 16 is then drawn against the arm of the handle to anchor the bushing tightly between the spaced arms of the handle 15. A lock nut 20 is then applied to the threaded end of the bolt to prevent the bolt 16 or bushing 11 from ever becoming accidentally loosened.

The disks 10, which are preferably formed of hardened steel or other suitable material, are provided with central apertures 21 which pass freely over a shank portion 22 of the hub 11. One end of the hub 11 is fashioned in the form of a flange 23 having flattened peripheral portions 24 to receive a wrench. The shank portion 22 of the hub is screw threaded 55 to receive a nut 25 to anchor the disks 10 securely upon the hub 11.

Each disk 10 is provided with a flat outer face and a rounded peripheral edge. The inner face of each disk is preferably of concavo-convex form. The central portion of the disk being concaved while the peripheral portion is convexed. A circular series of apertures 26 are formed in the disks 10. The radius of the series of apertures is virtually 60 equal to the radius of the concave portion of the disk so that the periphery of each aperture cuts both the concave and convex portions of the inner face of the disk. A pair of holes 27 are drilled in each disk 10. These holes preferably lie between the central aperture 21 and the circular series of apertures 26. It will be noted at this time that the holes 27 in the disks are so positioned that when they register the circular series of apertures 26 of one disk are staggered with relation to the apertures 26 of the other disk. A locking pin 28 is inserted into each of the aligned pairs of holes 27 to maintain the apertures 26 of the disks in staggered relation by preventing relative rotation of the disks 10.

The process of edging a blade by means of the present device is extremely simple and will be described in connection with a razor blade. The blade is preferably held in the 100

position indicated in Fig. 1 of the drawings. The edger is then applied so that the blade lies between the two disks and in the gap formed between the divergent convex portions of the disks. By applying a very light pressure upon the handle 15 and running the disks upwardly and downwardly along the blade it will readily be seen that the portion of the blade in contact with the convex part of one disk will be bowed slightly into an aperture 26 which lies directly opposite it. This wiping action of the convex portions of the disks across adjacent portions of the blade will work the fibres of the edge so acted upon into alignment. By removing the disks from engagement with the blade and turning the disks slightly before reapplying the disks to the blade it will be seen that the convex portions of the disks will each act upon a new portion of the blade to align a new series of fibres of the edge by their arcuate wiping action. The same result may also be obtained by turning the blade end for end to permit portions of the edge that were acted upon by the convex surface of one disk to now be acted upon by the convex portions of the other disk. I have found that by running the edger lightly back and forth over the blade a few times and then reversing the blade and repeating the operation a very keen edge may be restored upon a blade whose edge was very dull.

The staggered relationship of the circular series of holes is of real importance and this relationship serves a dual purpose. Firstly, it permits the portion of the blade lying across an aperture to be slightly bowed under the influence of the convex portion of the other disk to allow the gentle arcuate wiping action of that portion of the disk to effectively work the fibres of the edge into proper alignment. Secondly, the staggered relationship of the circular series of apertures insures against the accumulation of dirt or other foreign material between the disks by reason of the fact that the dirt particles wiped off of the blade by either the convex portion of the disk will be discharged through the apertures and not be directed between the disks.

Obviously the process of edging a blade in the manner above described will be greatly facilitated by the application of a small amount of lubricant to the blade to be sharpened. In addition to aiding the edging process the lubricant will prevent corrosion due to water deposits either on the blade or on the edging disks.

While the device portrayed in the accompanying drawings is particularly adapted for use in edging razor blades by slight modification of angle of the gap formed by the divergent convex portions of the disks the edger can be readily adapted for knife blades and other keen edged instruments.

It will readily be seen from the foregoing

description that an edger has been provided which is extremely simple in form, effective in operation, and one which may be produced at an extremely low cost. Furthermore the present device is capable of realigning the fibres of the edge of a dull blade to reestablish its keenness without abrasive action and as a further advantage the device is so designed that it automatically cleans itself in the course of reedging the blade.

While the device has been described in considerable detail in the foregoing specification it is understood that various changes may be made in its embodiment without departing from or sacrificing any of the advantages hereinafter claimed.

I claim:—

1. A blade edger comprising a pair of coaxial disks rotatable as a unit and cooperating to form an inwardly tapered peripheral gap for receiving the blade to be edged, each disk having a circular series of recesses adjacent said gap, the recesses in each disk being staggered with respect to those in the other disk and in overlapping relation therewith.

2. A blade edger comprising a pair of coaxial disks rotatable as a unit, the adjacent faces of the disks cooperating to form a peripheral gap for receiving a blade to be edged, there being a circular series of apertures in each disk, said apertures lying partially within the gap between said disks, said apertures in one disk lying in overlapping relation with said apertures in said other disk.

3. A blade edger comprising a pair of coaxial disks rotatable as a unit, the adjacent faces of said disks having convex portions cooperating to form a peripheral gap therebetween, there being a circular series of recesses in each disk, said series of recesses in one disk lying in overlapping relation with said series in said other disk.

4. A blade edger comprising a pair of coaxial disks rotatable as a unit, said disks having abutting faces of concavo-convex form, there being a circular series of apertures in said disks, said apertures lying partially within said concave portion and partially within said convex portion of said disks, and said apertures in one of said disks being staggered with relation to said apertures in said other disk.

5. A blade edger comprising a pair of coaxial disks rotatable as a unit, there being a circular series of apertures in each of said disks, means for preventing relative rotation of said disks to position said apertures in one disk in staggered relation with the apertures in said other disk, and convex portions on said disks cooperating to form a peripheral blade receiving gap.

6. A blade edger comprising a pair of coaxial disks, said disks having abutting faces of concavo-convex form, said concave por-

tion being centrally disposed on said disks, said convex portions merging with said concave portions and extending to the periphery of said disks, there being a circular series of recesses in each disk, and means for positioning said disks to provide a staggered relationship between the recesses of one disk with respect to the recesses of said other disk.

7. A blade edger comprising a pair of abutting axially aligned disks, there being a circular series of apertures in each of said disks, means for positioning the recesses in one disk in overlapping relation with the recesses in said other disk, a hub for anchoring said disks in abutting relation, a sleeve on which said hub and disks may rotate as a unit, a handle on which said sleeve is mounted, and means for anchoring said sleeve in said handle.

8. A blade edger comprising a pair of abutting coaxial disks rotatable as a unit, peripheral convex portions on said disks, said peripheral portions cooperating to form a blade receiving groove, there being a circular series of apertures in each of said disks, said series of apertures in one of said disks overlapping said series of apertures in said other disk, a trunnion on which said disks are rotatably mounted, and a handle on which said trunnion is mounted.

In witness whereof, I hereunto subscribe my name this 9 day of September, 1929.

FRIEDRICK GRAFFENBERGER.
